UNITED STATES PATENT OFFICE

2,558,988

RAILWAY LOCOMOTIVE DRIVING TRUCK

William M. Sheehan, Philadelphia, Pa., assignor
to General Steel Castings Corporation, Granite
City, Ill., a corporation of Delaware

Application May 3, 1948, Serial No. 24,907

4 Claims. (Cl. 105—157)

1

The invention relates to railway vehicles and more particularly to driving truck beds for vehicles, such as electric locomotives.

In one type of electric locomotive used heretofore, the draft gear is removed downwardly from the draft gear pocket in the vehicle bed. The brake rigging and other equipment just below the draft gear pocket must be removed before dropping the draft gear, which may require shop facilities not usually found in the ordinary running shed or inspection pit. Also, the draft gear pockets at the ends of the bed are connected by a center sill to carry buffing and pulling forces from one end of the bed to the other. Separate sand boxes may be attached to any convenient part of the bed.

One object of the present invention is to remove the coupler and draft gear from the draft gear pocket longitudinally of the bed and without removing the brake gear and other equipment.

Another object is to construct the draft gear housing with an integral bottom web to prevent the side walls from spreading laterally of the truck bed.

Another object is to transmit the buffing and pulling forces from one end sill to the other through the bed side members, instead of through a center sill.

Another object is to form sand boxes integral with the truck bed at the juncture of the side members and the end sills, thereby forming the sand boxes as part of the buffing and main carrying members.

Another object is to construct the sand boxes to obtain maximum strength without affecting their functional characteristics.

Another object is to provide a lighter, more compact driving truck bed.

Other objects will be apparent to those skilled in the art from the following description and accompanying drawings, in which:

Figure 1 is a top view of a railway vehicle driving truck constructed according to the invention and with portions of the truck bed cut away to show the construction more clearly.

Figure 2 is a side view of the truck showing one of the motor mountings in vertical longitudinal section.

Figure 3 is a horizontal section through the coupling structure and draft gear pocket taken approximately on the line 3—3 of Figure 2 and drawn to enlarged scale.

Figure 4 is a vertical longitudinal section through the coupling structure and draft gear

2

pocket taken approximately on the line 4—4 of Figure 1 and drawn to enlarged scale.

Figures 5 and 6 are vertical sections through a sand box at the left hand end of the truck in Figure 1 taken approximately at right angles to one another on the lines 5—5 and 6—6, respectively, and drawn to enlarged scale.

Figures 7 and 8 are vertical sections through a sand box at the right end of the truck in Figure 1 taken approximately at right angles to one another on the lines 7—7 and 8—8, respectively, and drawn to enlarged scale.

The truck includes wheel and axle assemblies 1 and journal boxes 2. A truck bed has end sills 3 and side members 4 connecting the end sills and provided with depending pedestal legs 5 for receiving journal boxes 2 between them. Electric motors E are secured to the axle housings and drive wheel and axle assemblies 1. A bolster 6 extends laterally of the truck between the side members and has a center plate 7 for mounting a car body center plate (not shown). Sand boxes 8, 9, 10, 11 at the corners of the truck bed are cast integral therewith at the junctures of the side members and end sills and form the sole connections therebetween.

Sand boxes 8, 9 at the left hand end of the truck bed (Figures 1, 2, 5, 6) each comprises a hollow receptacle having a top wall 12, an inclined bottom wall 13, an outer diagonal side wall 14, an inner curved side wall 15, and end walls 16, 17. Top wall 12, bottom wall 13, and outer and inner side walls 14, 15 form the top, bottom, outer and inner faces of the corresponding truck bed portions, respectively. A substantial portion of sand boxes 8, 9 extend into end sill 3 and the box end walls 16, 17 form reinforcing ribs for the associated sill 3 and side members 4, respectively. A sand filler pipe 18 extends upwardly and outwardly of the bed from top and outer side walls 12, 14 and an outlet 19, in bottom wall 13, provides for discharging sand to the rail.

Sand boxes 10, 11, at the right hand end of the truck bed (Figures 1, 2, 7, 8) extend diagonally between the associated end sill 3 and side members 4. Each sand box 10 and 11 forms a hollow receptacle having a top wall 20, an inclined bottom wall 21, an outer side wall 22, an inner side wall 23, and end walls 24, 25. Top wall 20, bottom wall 21 and side walls 22, 23 form the bounding walls of the corresponding truck bed portion and end walls 24, 25 form reinforcing ribs for the truck bed portion. A sand filler pipe 26 extends upwardly and outwardly of the

truck frame from top wall 20 and outer side wall 22. An outlet 27 in bottom wall 21 is provided for discharging sand to the rail.

Sand boxes 8, 9, 10, 11 form part of the buffing and main carrying members. This saves weight and at the same time accommodates the sand boxes without, in any way, reducing the load carrying sections.

Sill 3 at the right hand end of the truck (Figures 1 and 2) has an articulated connection 28 to an adjacent truck (not shown).

A draft gear pocket 29 is formed in end sill 3 at the left hand end of the bed as a structural part thereof and includes integral webs forming the top 45, bottom 46, and side walls 47, 48 of the pocket. Draft gear pocket 29 extends longitudinally of the truck and opens forwardly of end sill 3, at 30, and projects inwardly of transverse, vertical wall 31 of the end sill, substantially abreast of the adjacent pedestal leg 5 and beyond brake hanger brackets 51.

A draft gear 32 is received in pocket 29 and is held therein by follower stops 33 secured to the side walls of the draft gear pocket by retainer bolts 34. A coupler 35 has a head 36 extending forwardly of end sill 3 and has a shank 38 extending into pocket 29 and secured by a key 37 to the draft gear. A filler block 39 is bolted to end sill 3 in pocket 29 adjacent opening 30, and a wear element 40 is dowelled to filler block 39 and supports the outer end of coupler 35.

Coupler 35 and draft gear 32 may be readily removed from draft gear pocket 29 through opening 30 as follows:

Key 37 is removed and coupler 35 is withdrawn through opening 30 from pocket 29. Element 40 is lifted from filler block 39 and filler block 39 is unbolted from end sill 3 and both are removed through opening 30. A fixture (not shown) of any suitable kind, is attached to the outer end of the draft gear to compress it sufficiently to relieve the pressure on follower stops 33. Retainer bolts 34 then are removed and follower stops 33 are withdrawn through opening 30. The compression of the draft gear is eased by releasing the fixture and the fixture and draft gear are removed through opening 30.

With this arrangement, it is unnecessary to remove a brake beam 41 directly below draft gear pocket 29 and associated brake gear 42, 43, 44 as would be necessary if the coupler and draft gear were removed from the draft gear pocket downwardly from the truck bed.

Furthermore, the draft gear pocket may be provided with a housing that completely surrounds the draft gear, and integral bottom web 46 makes possible a lighter structure for the same strength as compared to the structures used heretofore where the bottom of the draft gear pocket was open or was provided with a removable wall so that the draft gear and coupler could be dropped through the bottom opening. If desired, the shaft for brake lever 49 may be journaled in bearings 50 integral with and depending from bottom web 46 and side webs 47, 48.

In the arrangement described, no center sill is required, the side members being of sufficient strength to transmit the buffing and pulling forces from one end sill to the other.

While the above description is explicit as to some of the details of the structure, it will be understood that these details are not essential to all embodiments of the invention but the structure may be modified substantially without departing from the spirit of the invention, and the exclusive use of such modifications as come within the scope of the claims is contemplated.

What is claimed is:

1. In a railway vehicle truck bed, an end sill member, a side member, and a sand box including a hollow receptacle having its walls extending diagonally between and formed integral with said members and adapted to transmit between said members draft and buffing forces applied to the truck.
2. In a railway vehicle truck bed, end sills, side members, diagonal members integral with and forming the sole connections between the end sills and side members and each comprising a sand box.
3. In a railway vehicle truck bed, end sills, side members, diagonal members connecting said sills and side members and each including a hollow receptacle forming a sand box having its walls formed integral with and joining the associated side member and end sill, the upper and outer side walls having portions extending upwardly and outwardly of the bed and forming a filler spout, and the bottom wall having an outlet for discharging sand to the rail.
4. In a railway vehicle truck bed, an end sill, side members, and diagonal members connecting said sill and side members and cooperating with said sill and side members to form sand boxes, said diagonal members forming the sole connection between said sill and side members.

WILLIAM M. SHEEHAN.
